(57) **CLAIM**

The ornamental design for a refrigerator, as shown in the accompanying drawings and as described above.

DESCRIPTION

FIG. 1 is a perspective view of a refrigerator;
FIG. 2 is another perspective view of the refrigerator of FIG. 1;

FIG. 3 is a front elevation view of the refrigerator of FIG. 1;
FIG. 4 is a right side elevation view of the refrigerator of FIG. 1;

FIG. 5 is a left side elevation view of the refrigerator of FIG. 1;

FIG. 6 is a top plan view of the refrigerator of FIG. 1; and

FIG. 7 is a bottom plan view of the refrigerator of FIG. 1.

The views of the refrigerator not shown form no part of the claimed design. The broken lines shown herein are for illustrative purposes and form no part of the claimed design.
